UNITED STATES PATENT OFFICE.

THEODORE H. BAUCK, OF WATERBURY, CONNECTICUT, ASSIGNOR TO THE E. J. MANVILLE MACHINE COMPANY, OF WATERBURY, CONNECTICUT, A CORPORATION OF CONNECTICUT.

BOLT-TRIMMING MACHINE.

Application filed October 25, 1927. Serial No. 228,552.

This invention relates to a machine for trimming the heads of bolt and cap-screw blanks.

The object of the invention is to provide a blank trimming machine of the general type of those illustrated and described in patent to Campbell No. 959,455, May 31, 1910, and reissue patent to Riley No. 16,522, January 4, 1927, which will be more rapid and surer in action, and which will more perfectly trim the heads than the prior machines.

In machines of this nature the blank is fed into line with a trimming die fixed in the frame and a tubular punch which is carried by a gate that is reciprocated in the frame toward and from the die, the shank of the blank entering the punch and the punch forcing the head of the blank into the die.

In the present invention the gate which holds the punch and which is forced forward by a cam carries two independently movable slides, a rear slide that is forced forwardly by a cam and a forward slide that holds a pin which extends through the punch and that is forced forwardly positively for a portion of its travel by the rear slide and then is thrown forward still further by a lever and spring. When the gate is forced forward by its cam the pin pushes the head of the blank against the trimming die and as the gate continues its forward movement the shank of the blank enters the punch, the pin retreating until the forward end of the punch engages the under side of the head of the blank and forces the blank head into the trimming die, the punch not entering the die. Following this the rear slide by its cam is forced into engagement with the front slide and moves it forward until the pin pushes the blank head completely through the trimming die, at which time the friction of the head of the blank in the die is so relieved that the pin will be quickly thrown forward by the lever and spring and drive the shank of the blank completely through the trimming die.

The frame, blank feeding means and driv-

ing mechanism are not illustrated in detail in the drawings as users of this type of machines are thoroughly familiar with these elements and they may be of any of the well known designs.

Fig. 1 shows a central vertical section of the gate, punch, pin, forward or knock out slide, rear or kicker slide and the means for actuating these parts, and also the trimming die and feed fingers with a blank indicated as fed between the punch and die.

Fig. 2 is a similar view showing the parts with the punch forward and the head of the blank forced into the trimming die.

Fig. 3 shows a horizontal section of the gate and the parts carried thereby.

Fig. 4 is a section showing the positions of the parts with the pin thrown forward as after a blank has been knocked out of the trimming die.

In the drawings 1 indicates the gate which is supported and reciprocated in the frame 2 as is common in headers and trimmers. The gate at its rear end has two rolls 3 which are adapted to be engaged for forcing the gate forward at the proper time by a pair of cams 4 fastened on the main shaft 5 of the machine. Movable in the rear end of a central opening in the gate is the rear, or kicker, slide 6. At the back end this slide has a roll 7 that is engaged by a cam 8 fastened on the main shaft between the gate cams 4. At the front end this slide has a cross head 9 with two forwardly extending rods 10 on which are springs 11 tensioned to, through the cross head, force the kicker slide backward and hold the roll 7 in engagement with the kicker cam 8. In the central opening in the gate in front of and aligned with the kicker slide is the forward, or knock out, slide 12 and extending forwardly from this slide through a bushing 13 and into the punch 14 is the knock out pin 15. In a mortise 16 in the knock out slide 12 is a block 17 that has trunnions 18 on the ends of which are blocks 19 that are fitted in the forked upper ends of a yoked lever 20. This lever is pivoted on a shaft 21 that is fixed in

the frame and its upper end extends through openings 22 (Fig. 3) in the gate, while its lower end is connected with a rod 23 on which is a spring 24 that is tensioned so as to normally thrust the lower end of the lever rearward and the upper end of the lever forward. The block 17 is fastened to the knock out slide 12 by a shear pin 25 which is sufficiently strong to sustain all of the strains of normal operation but which will break and release the connection between the lever and the knock out slide should a blank become wedged in the die or should any other obstruction interfere with the forward movement of the knock out slide and pin.

With the machine tooled as above described the blank 26 is fed, for example, by a parallelogram feed movement 27 of the character shown in the Campbell patent before mentioned, into line with the trimming die 28 and the punch 14, as illustrated in Fig. 1. In operation the cams 4 advance the gate and the pin 15 presses the blank head against the face of the trimming die. As the forward movement of the gate and punch continues the shank of the blank presses back the pin and enters the punch, the spring 24 and lever 20 yielding to permit this. When the punch engages the head of the blank it forces the head into the trimming die until the end of the punch reaches the face of the die, as illustrated in Fig. 2. At this time the forward movement of the gate ends and the cam 8 then forces the kicker slide 6 into engagement with the knockout slide 12 and pressing it forward causes the pin to drive the blank until its head is forced through the die and the trimming completed. When the trimming is completed the friction between the blank head and die is relieved allowing the spring 24 through the lever 20 to throw the knock out slide and pin forward quickly to the position illustrated in Fig. 4, and drive the shank of the blank completely through the trimming die. The gate then returns and the cycle of movements repeated. As the gate moves back a stop 29 engages the forward end of the knock out slide 12 and pushes it back with the gate. The engagement of studs 30 and 31 on the lever 20 with the stops 32 and 33 on the frame limits the movements of the lever 20.

With the mechanisms described the punch causes the major part of the trimming of the head of the blank but as it does not enter the die it does not complete the trimming. The kicker cam and slides, which are aligned with the pin and blank, cause the pin to positively drive the blank head through the die and complete the trimming. As the punch backs up the metal under the head of the blank while the kicker cam is operating and the pin is completing the trimming, the metal at the rear edges of the head is not

torn off but is cleanly cut. The kicker cam being centrally located in the gate and in line with the pin and blank, the strains are such that a powerful action may be obtained for finishing the trimming with a relatively small pin. Should a blank become wedged the shear pin immediately breaks and releases the knock out slide so that the pin will not become damaged.

The invention claimed is:

1. In combination in a blank trimming machine, a fixed trimming die, a reciprocating gate, cams for forcing the gate toward the die, a tubular punch carried by the gate, a slide carried by and movable independently in a central opening in the gate, a pin actuated by the slide and movable through the punch, a cam located between the gate operating cams for forcing said slide toward the die independently of the gate, and spring means adapted to move said slide forward independently of the gate, further than the throw of said slide operating cam.

2. In combination in a blank trimming machine, a fixed trimming die, a reciprocating gate, means for forcing the gate toward the die, a tubular punch carried by the gate, a slide carried by and movable independently in a central opening in the gate, a pin actuated by the slide and movable through the punch, a cam located in line with the axis of the gate for forcing said slide toward the die independently of the gate, and spring means adapted to move said slide forward independently of the gate, further than the throw of said slide operating cam.

3. In combination in a blank trimming machine, a fixed trimming die, a reciprocating gate, cams for forcing the gate toward the die, a tubular punch carried by the gate, a kicker slide and a knock out slide carried by and movable independently in a central opening in the gate, a pin actuated by the knock out slide and movable through the punch, a cam located between the gate operating cams for forcing the slides towards the die independently of the gate, and spring operated means adapted to move said knock out slide independently of the kicker slide and the gate.

4. In combination in a blank trimming machine, a fixed trimming die, a reciprocating gate, means for forcing the gate toward the die, a tubular punch carried by the gate, a plurality of aligned slides carried by and movable independently in a central opening in the gate, a pin held by the forward of said slides and movable through the punch, a cam located in alignment with said slides for forcing the slides towards the die independently of the gate, and spring operated means adapted to move the front slide independently of the back slide and the gate.

5. In combination in a blank trimming machine, a fixed trimming die, a reciprocat-

ing gate, means for forcing the gate toward the die, a tubular punch carried by the gate, a plurality of aligned slides carried by and movable independently in a central opening in the gate, a pin held by the forward of said slides and movable through the punch, a cam located in line with said slides

for forcing the slides toward the die independently of the gate, a lever and spring for moving the front slide toward the die independently of the back slide and the gate, and breakable means connecting said lever with said front slide. 10
